W. B. WALKER, OF SALEM, IOWA.

Letters Patent No. 69,516, dated October 1, 1867.

IMPROVEMENT IN LOOMS.

The Schedule referred to in these Letters Patent and making part of the same.

TO ALL WHOM IT MAY CONCERN:

Be it known that I W. B. WALKER, of Salem, in the county of Henry, and State of Iowa, have invented a new and useful Improvement in Looms; and I do hereby declare that the following is a full, clear, and exact description thereof, which will enable others skilled in the art to make and use the same, reference being had to the accompanying drawings, forming part of this specification, in which—

Figure 1 represents a plan or top view of this invention.

Figure 2 is a transverse vertical section of the same, taken in the plane indicated by the line *x x*, fig. 1.

Figure 3 is a front view of the same.

Figure 4 is a sectional end view of the same.

Similar letters of reference indicate like parts.

A represents the arms or extensions of the lay. *bb* is a downward projection on the outer end of each arm of the lay, to which are pivoted the pickers or drivers *ff*. *cc* are springs, attached to the under side of each arm of the lay, and fastened near the swords for the purpose of operating the pickers *ff*. *dd* are arms or projections extending at right angles from the pickers, and with their upper edges so shaped that the convex surface of the outer ends of the springs *cc* will bear upon the convex portion of the arms throughout the entire movement of the pickers with the full power of the springs. The upper part of the pickers *ff* extends up through slots *vv*, in the ends of the extensions of the lay, into a mortise in the picker-blocks *gg*, for the purpose of driving the shuttle from side to side of the web. The lower points of the pickers *cc*, as the lay is brought forward, pass around the bent ends and to the inner side of the springs *ii*, and as the lay moves backward they are received by the set-springs (or catches) *rr*, and the pickers are held on the half-set while the lay is back. As the lay comes forward the set-springs follow, and the lower end of the picker is received by the guide-spring *jj*, and is guided beyond the end of the springs *kk*, then at the backward motion of the lay it is guided to the back end of said springs *kk*, where it flies off and the picker-blocks *gg* hit the shuttle and throw it to the other side of the web. Thus the pickers alternate and drive the shuttle back and forth by means of the combined motion of the lay, pickers, and springs, as described. When one picker drives the shuttle from one end of the lay the other is held by the set-spring or catches in the other end of the lay, ready to be released at the next backward movement of the lay and send the shuttle back. After the picker passes beyond the guide-spring *jj* the spring closes behind it, and guides the picker during the next forward movement of the lay beyond the end of the spring *kk*, which presses against the spring *jj* and compels the picker-arm in its backward movement to pass to the outer side of the spring *kk* and thus complete its backward movement, where it comes in contact with spring *ii* to prevent its returning by the same way, and thus facilitating the setting of the picker for driving the shuttle. The set-springs or catches *rr* are so constructed that they form at their upper ends a right angle. The outer leg of the angle which holds the picker on the set is received between the ends of the springs *ii* and *jj*, in a place, *88*, prepared for it on the inside of the back end of the spring *ii*. The springs pass down through mortises *tt* in the platform *ll*, and are fastened to elbows *ss*. The elbows are fastened to the bottom of the platforms, and the platforms are fastened on the top edge of the side pieces of the loom, for the purpose of holding the guide-springs. The pickers are pivoted by bolts passing through the downward projections *bb*. There is a slot, *vv*, in the end of each arm of the lay, for the purpose of giving the picker sufficient motion to drive the shuttle. The guide-springs *ii*, *jj*, and *kk* may be fastened to the platform by means of metal plates, as shown, or they may be fastened to strips of wood and then fastened to the platform. The guide-springs are arranged and set on the platform in such a manner as that each spring shall give more set to the picker as it passes from one to the other, or they may be set so that one or two of them may give the full set, each spring closing behind the picker as it passes to prevent its returning until it has hit the shuttle. The springs *ii* are bent outward at the loose or outer ends, and turned in at the top edge, so as to be somewhat spiral-shaped, to receive the end of the picker as the lay passes back and forth, and commence to give the set to the picker. The projections *uu*, under the sides of the loom, and attached to them, form the bearings for the pivots of the swords of the lay, so as to give more sweep to the picker-motion on the guide-springs, thereby giving sufficient motion to the picker to force the shuttle from side to side of the web.

*7 is a cloth-beam, with the bearing on the end passing through and extending beyond the side of the loom, and to this bearing is attached a spring, *xx*, in form of a clock-spring, which, when wound up, will in unwinding*

take up the cloth just as fast as it is woven and convey it to the receiving-beam below. The spring takes up the slack portion of the cloth produced by the beating up of the lay. 2 is a loose ratchet-wheel, having on the back side a pin to which the outer end of the spring is attached, and is wound up by turning the ratchet-wheel and secured by means of the handle 5. 6 is a detent or pawl, to hold the spring when wound up. 3 is a ratchet-collar, made of iron and fast to the axle or gudgeon of the beam, and the spring is held wound up by the catch 4, so that it has no power. When you want to turn the beam, you raise the pawl 6 clear from the ratchet-wheel 2, and the beam may be turned either way and the cloth wound off, if required. Raise the pawl 6 clear from the ratchet-wheel 2, and the spring can be wound up, and yet the beam is at liberty to roll either way. When you want to weave again drop detent 6 into ratchet 2, and throw off catch 4 from ratchet-collar 3, and the force of the spring 1 will turn the beam. The spring is again on the clean-beam 7, and you are ready again for weaving. Should the spring prove too strong I apply a brake, 15, to the cloth-beam, as seen in the drawing. The surface of the cloth-beam 7 is provided with short pins, or covered with cards to make it sufficiently rough to retain the cloth as the beam turns, and thus take up the same and convey it to the beam below, the outer end of the cloth being fastened to the lower beam. The lower or extra beam may be placed below, or above, or in any position most convenient to take-up beam, as shown in the drawing. The web will pass behind both beams, under the lower beam, then up over the take-up beam 7, down behind it, and it is fastened to the lower beam by the extra beam. The rough surface of the take-up beam 7 takes up the cloth, and the cloth acts as a belt to turn the lower beam. The lower beam receives all the cloth as fast as woven, and does not interfere with the take-up beam, and the increase of its diameter, as is the case where but one beam is used, the cloth simply passing over the upper surface of the take-up beam. This extra beam I will call the receiving-beam. What I claim as my invention, and wish to secure by Letters Patent, is -

1. The construction and arrangement of the downward projecting arms *b b* slotted longitudinally, in which are received the pickers *f f* are pivoted, and supporting the picker-blocks *g g*, which are mortised to receive and enclose the main springs *c c* at their upper ends of said pickers as herein shown and described, for the purpose specified.
2. The pickers *f f*, one in the end of each arm or exterior of the lay, with the projections or arms *d d*, having a convex point, and being concave from that to the main body of the picker, substantially as described and for the purposes set forth.
3. The main-springs *c c*, with the outer end convex or bent up to work on the convex point of the projections or arms *d d* of the arms of the picker, substantially as described and for the purposes set forth.
4. The arrangement and combination of the platforms *l l* fastened on the top of the sides of the loom, with the set-springs *i i*, *j j*, and *k k*, also the set-springs or catches *r r*, and elbows *s s*, to which the set-springs are attached, substantially as described and for the purposes set forth.
5. The cloth-beam *7*, with the ratchets *2* and *3* attached, and the surface covered by cards or filled with short pins, the spring *s' s'* and pawls *4* and *6*, substantially as described and for the purpose set forth.
6. The extra cloth-beam or receiving-beam, on which the web will be received by the action of the take-up beam, in combination with the take-up beams, constructed and operated as described.

W. B. WALKER.
